UNITED STATES PATENT OFFICE.

ARTHUR L. STEVENS, OF CHICAGO, ILLINOIS.

ANNEALING-FURNACE.

1,219,499.

Specification of Letters Patent. Patented Mar. 20, 1917.

Application filed September 10, 1912. Serial No. 719,527.

To all whom it may concern:

Be it known that I, ARTHUR L. STEVENS, a citizen of the United States, residing at Chicago, in the county of Cook and State of Illinois, have invented certain new and useful improvements in Annealing-Furnaces, of which the following is a specification.

The invention relates to regenerative furnaces and particularly to annealing furnaces of the regenerative type, and it consists in certain novel arrangements and devices in furnace construction constituting improvements in certain respects, to be hereinafter more fully described, upon known furnaces of this character.

One of the objects of the invention has been to provide a regenerative furnace, for annealing or other similar purposes which can be built entirely or very largely above the ground. Furnaces of this sort usually have their regenerators located under the heating chamber, which necessitates considerable excavation in case the heating chamber is on the ground level. If the furnace is erected on low ground or near the water level, this necessitates expensive waterproofing. The invention has for a further object to provide an annealing furnace in which the combustion takes place above the articles treated so that the flames do not impinge directly thereupon.

A further object is to provide, in a furnace for annealing or like purposes, the hearth of which is removable and supported on a truck or the like, certain constructions and arrangements whereby the truck is borne directly on a foundation so that it does not subject the furnace structure to any stresses.

The invention has for a further object to provide an annealing furnace of novel and improved construction which will be economical in fuel, compact in structure, effective in its operation and which in particular is so constructed and designed as to impart a uniform temperature to all of the articles treated.

The invention has for a further object to provide certain novel arrangements for reversing the drafts through the regenerators and annealing chamber which are improvements upon known furnaces in respect particularly to economy of construction and simplicity of operation.

The invention has for a further object to provide a regenerative furnace having the improved features and consisting of the

novel combinations, arrangements and devices shown in the drawings hereto annexed and which will be hereinafter more particularly described and claimed.

The invention is illustrated in a preferred embodiment in the accompanying drawings, wherein—

Figure 1 is an end elevation of the furnace;

Fig. 2, a longitudinal, sectional view taken on the line 2—2 of Fig. 1 looking in the direction of the arrows;

Fig. 3, a sectional plan taken on line 3—3 of Fig. 2;

Fig. 4, a sectional plan taken on line 4—4 of Fig. 5;

Fig. 5, a cross-sectional view taken on line 5—5 of Fig. 3 looking in the direction of the arrows;

Fig. 6, an enlarged detail view illustrating particularly the construction and arrangement of the burners;

Fig. 7, a sectional view taken on line 7—7 of Fig. 8 looking in the direction of the arrows;

Fig. 8, a sectional view on line 8—8 of Fig. 3 looking in the direction of the arrows;

Fig. 9, a similar view taken on line 9—9 of Fig. 8;

Fig. 10, a detail section illustrating a modified form of burner adapted for consuming gas instead of oil, the section being taken on line 10—10 of Fig. 11 looking in the direction of the arrows; and

Fig. 11 is a similar view taken on line 11—11 of Fig. 10.

Like characters of reference designate like parts in the several figures of the drawings.

The furnace is made of the usual brick work walls and roof reinforced by a structural frame 25. It is built upon a suitable foundation such as the concrete base 26 shown in the drawings. The front end of the furnace is open in order to admit a truck 27 which runs upon the rails 28 and is provided with a platform 29 formed of fire-brick or the like on which the articles to be treated are placed and which constitutes the

hearth of the furnace. The truck and its load are borne directly by the foundation, the furnace structure being subjected to no stress. The opening in the front of the furnace above the platform 29 of the truck is closed by a door 30 which may be raised and lowered by any suitable mechanism. I have

shown for this purpose cables 31, 31' which pass over sheaves 32, 32' and are connected with a cable 33 which, passing over the sheaves 34, 35, is connected to the piston rod 36 of an air motor the cylinder of which is designated 37.

Seals are provided for effectively separating the space below the platform of the truck from the heating or annealing chamber 38, these seals consisting of troughs 39 filled with sand into which project flanges 40 depending from the platform 29 of the truck.

The lower portions of the side walls 41 of the furnace are formed with recesses 42 and the walls above these recesses are divided so as to provide walls 43, 43'. The spaces between the bridge walls and the side walls of the heating chamber constitute flues or combustion chambers 44, 44' having openings 45 at the bottom communicating with the recesses 42. In these recesses are located the oil burners 46, oil being conducted to the burners through pipes 47 and air or dry steam through pipes 48.

The regenerators 49, 49', filled with the usual checker work, are located at the end of the furnace opposite the door 30. Extending beneath the furnace through the concrete base 26 are the flues 50, 50' leading from the regenerators 49, 49', respectively. The flues communicate with the combustion chambers 44, 44' leading into the heating chamber by means of distributing flues 51, these latter flues converging in pairs above the openings 45 under which are located the burners 46. Fire-brick dampers 52 guided in suitable slots in the brick work are slideable back and forth so as to control the amount of air admitted to the heating chamber through the several flues 51. A proper adjustment of these dampers distributes the air lengthwise of the furnace and prevents short-circuiting through one end of the heating chamber. The bridge walls 43, 43' are preferably formed with openings 53 at substantially the level of the top of the truck.

Arranged on the brick work directly above the regenerators 49, 49' is a valve casing 54 with which the regenerators are in communication through openings 55, 55'. The valve casing is open at both ends and supports at the middle a smoke stack 56. Extending longitudinally through casing 54 is a rod 57 which is longer than the casing and is provided at opposite ends with the valves 58, 58' and at the middle with a valve 59. With the valves in the position shown in Fig. 9 fresh air may enter the regenerator 49' through the opening 55'. The other end of the casing is closed by valve 58. Valve 59 stands at a position between the stack and opening 55' and closes communication between the regenerator 49' and the stack

while opening the communication between regenerator 49 and the stack. The valves 58, 58', 59 and rod 57 are slideable back and forth through the casing 54. When moved to the position at the extreme right from that shown in Fig. 9, regenerator 49 is opened to the atmosphere and the fresh air intake of regenerator 49' closed and this regenerator put into communication with the stack. The rod 57 and its valves may be moved by any suitable means. I have shown cables 60 attached to the valves 58, 58' and passing over sheaves 61. The reversing valve mechanism above described is not claimed *per se* herein as it forms the subject-matter of an application, Serial No. 719528, filed by me on September 10, 1912.

Gas burners may be used instead of the oil burners 46. Figs. 10 and 11 show certain modifications which are necessary if gas is to be burned instead of oil. 62 designates the gas main and 63 branch pipes leading into the chambers or spaces 64 under the flue or combustion chamber 44 or 44', as the case may be. The spaces 64 are closed up in front by brick work 64'. A baffle brick 65 extends over the opening 66 by which the gas enters the flue 44, the brick 65 resting upon the transversely placed bricks or blocks 67 which are spaced apart as shown in Fig. 10.

One of the advantages of the furnace construction shown and described is that it may be used either with gas as a fuel or with oil, the change from one fuel to the other involving very simple modifications in the structure of the furnace that can be readily and cheaply made. The oil burners, it will be noted, are located in spaces directly under the vertical flues or combustion chambers 44, 44'. Supposing the furnace is equipped for oil, if it is desired to change to gas it is only necessary to remove the oil burners and make the slight changes shown in Figs. 10 and 11.

Another advantage of the furnace construction shown is that it dispenses almost entirely with the use of arches and hence does away with the thrusts incident to arch construction. The only arch is the roof arch 68 and this is supported on the angle irons 69 (Fig. 5) which are carried by the structural steel framer. Instead of using arches for the flues 50, 50' I "cobel" the brick work as indicated at 70. A similar construction is provided for the brick work constituting the distributing flues 51.

The design of the furnace is such that the truck and its load are borne directly upon the foundation 26. No stresses or pressures are exerted against the furnace structure proper.

The operation of the furnace above described is as follows: The truck 27 loaded with the castings or other articles to be an-

nealed or otherwise treated is pushed into the furnace and the door 30 lowered. With the controlling valves for the regenerators in the position shown in Fig. 9, fresh air enters 5 through the checker work in the regenerator, thence through the flue 50', through the flues 51 into the flue or space 44', and into the heating chamber 38. The air entering the space 44' is mixed with the fuel from the burners 10 which are lighted on this side of the furnace and combustion takes place. The space 44' constitutes a combustion chamber which extends the length of the heating chamber 38. The draft carries the flames from the combustion chamber 44' up to the roof 68 of the furnace, and the flames reverberate across the top of the chamber under the arched roof out of contact with the work on the hearth 29. The heating of the work 15 is done by radiation. There is practically no direct impingement of the flame upon the articles annealed. The gases from the heating chamber pass down through the flue 44, as seated, and thence go to the regenerator 20 49, through flue 50 and thereafter through opening 55 to the stack 56. In being drawn down through the space 44 by the stack draft some of the flames and hot gases pass 25 through the openings 53 in the bridge walls 30 43, which tends to keep the heat close to the work.

When the position of the valves 58, 58' is reversed the circulation through the regenerators and through the furnace is reversed. 25 The fresh air is taken into regenerator 49 through the opening 55, passes through the checker work of the regenerator and becomes preheated thereby, enters the heating chamber through flue 44 where it is mixed with 30 the fuel from the burners on this side of the furnace, which are now firing, the burners on the other side having been extinguished. The furnace gases now escape through flue 44' and pass out the stack through the regenerator 49'. Flues 51 which open out of the lengthwise extending flues 50, 50' at intervals along said flues serve to distribute the air entering the heating chamber. The amount of air admitted through the several 45 flues 51 may be controlled by an adjustment of the dampers 52. This is necessary particularly so as to prevent short circuiting through the end of the heating chamber nearest the regenerators. The flues or ducts 50 55 51 are arranged so that the streams of air entering the flues 44, 44' converge directly over the burners. This insures a thorough mixing of air and fuel and results in complete combustion.

60 While I have described my invention in certain preferred constructions, it will be understood that modifications might be made without departing from the principles of the invention. Therefore, I do not

wish to be understood as limiting the invention to the particulars shown and described.

I claim:

1. In a furnace of the character described, the combination with a heating chamber, of regenerators all arranged at one end of said chamber and on substantially the same level therewith, and flues extending from said regenerators under the heating chamber and communicating with the same at opposite sides of said chamber.

2. In a furnace of the character described, the combination with a heating chamber, of regenerators arranged at one end of said chamber and on substantially the same level therewith, a door at the other end of said chamber, flues arranged below said chamber on opposite sides thereof and communicating with said regenerators, and distributing flues between said first named flues and said chamber.

3. In a furnace of the character described, the combination with a heating chamber, of regenerators arranged at one end of said chamber and on substantially the same level therewith, a door at the other end of said chamber, flues extending from said regenerators along and below opposite sides of said chamber, and distributing flues leading substantially vertically from said first named flues to opposite sides of said chamber.

4. In a furnace of the character described, the combination with a heating chamber having a door at one end, of a pair of regenerators at the other end of the chamber, bridge walls within the chamber spaced from the sides thereof so as to constitute combustion spaces, a flue extending from each regenerator under one of said combustion spaces, and distributing flues connecting said first named flues with said spaces, respectively.

5. In a furnace of the character described, the combination with a heating chamber having a door at one end, of a pair of regenerators at the other end of the chamber, bridge walls within the chamber spaced from the sides thereof so as to constitute combustion spaces, a flue extending from each regenerator under one of said combustion spaces, distributing flues connecting said first named flues with said spaces, respectively, and means for introducing fuel into the bottom of said combustion spaces.

6. In a furnace of the character described, the combination with a heating chamber formed with bridge walls spaced away from the side walls thereof so as to constitute combustion spaces, of a pair of regenerators at one end of said chamber, and flues leading from said regenerators along the sides of the furnace, flues connecting said first named flues with said combustion spaces,

and means for obtaining a uniform distribution of air through said connecting flues.

7. In a furnace of the character described, the combination with a heating chamber 5 formed with bridge walls spaced from the side walls thereof constituting combustion spaces, of a pair of regenerators at one end of said chamber, flues leading from the regenerators along the sides of the furnace, 10 pairs of converging distributing flues leading from said first mentioned flues to said combustion spaces, and means for introducing fuel into said spaces at substantially the points of convergence of said distributing 15 flues.

8. In a furnace of the character described, the combination with a heating chamber, of a pair of regenerators, flues connecting the regenerators with opposite sides of the heating chamber, a casing arranged above the regenerators with which each communicate, 20 a stack supported on said casing, and a valve element movable in said casing which in alternative positions places each regenerator alternately in communication with the atmosphere and the other in communication 25 with the stack.

9. In a furnace of the character described, the combination with a heating chamber 30 open at one end, of a door which closes said open end, bridge walls in said chamber spaced from the sides thereof to constitute combustion spaces, a pair of regenerators located at the end of the chamber opposite 35 the door, flues below the chamber extending

from said regenerators along the sides of the furnace, distributing flues leading substantially vertically from said first named flues into the spaces between the bridge walls and the sides of the furnace, means for introducing fuel into the combustion spaces, and valve apparatus adapted in alternative positions to cause a circulation through the regenerators and the heating chamber alternately in opposite directions.

40

10. In a furnace of the character described, the combination with a foundation, of a furnace structure providing a heating chamber having bridge walls so as to constitute combustion spaces extending the 50 length of the heating chamber, said furnace being open at one end, a door closing the opening in the end of said furnace, regenerators located at the other end of the furnace substantially above said foundation, flues 55 leading from said regenerators under said combustion spaces, distributing flues leading substantially vertically from said first named flues to said combustion spaces, means for introducing fuel into said combustion spaces 60 between the several distributing flues, means for equalizing the flow of air through said distributing flues, and means for periodically reversing the circulation through said heating chamber and regenerator.
